UNITED STATES PATENT OFFICE.

AXEL L. RUTQUIST, OF WALLACE, IDAHO.

RAFTER-MITER.

1,236,486.

Specification of Letters Patent. Patented Aug. 14, 1917.

Application filed October 18, 1916. Serial No. 126,404.

To all whom it may concern:

Be it known that I, AXEL L. RUTQUIST, a citizen of the United States, residing at Wallace, in the county of Shoshone and 5 State of Idaho, have invented certain new and useful Improvements in Rafter-Miters, of which the following is a specification.

My invention relates to improvements in rafter miters, and the object of my invention is the provision of a device of this character especially designed to enable a workman to quickly, accurately, and automatically determine the angles of various correlated rafter cuts, without having to resort 10 to the old cut and try method, or to the use of difficult and time consuming mathematical calculations.

It is well known that the work of laying out of rafters in the usual way by the use 20 of an ordinary square for securing the desired rise and run or the proper lines for the ridge and plate cuts, requires considerable skill, mathematical knowledge, and great care in order to avoid serious errors. With 25 my device it is possible for a carpenter of ordinary intelligence to readily ascertain the angles of the desired cuts with absolute unerring accuracy.

Broadly, I provide an instrument which is 30 capable of various adjustments in planes angularly related to a stock, the adjustable elements comprising a plurality of straight-edges or arms pivotally and slidably mounted in said stock and so connected and 35 coördinated that the movement and adjustment of one arm will serve to automatically adjust the remaining angle members so as to indicate the proper cuts for the several types of rafters.

40 The use of my invention will be herein-after fully explained, and the construction of one form or embodiment thereof specifically described, recourse being had to the accompanying drawings, in which—

45 Figure 1 is a longitudinal side elevation of the device as it appears with the angle or miter arms incased inoperatively within the stock.

Fig. 2 is a longitudinal sectional view of 50 the stock taken on line 2—2 of Fig. 3, and showing the straight-edges withdrawn from the stock and set for a half or 45 degree angle where the pitch begins, the dash-lines indicating the arms positioned for a cut of 55 different angle.

Fig. 3 is a somewhat enlarged transverse sectional view on line 3—3 of Fig. 1, and

Fig. 4 is a greatly enlarged fragmentary transverse sectional view of Fig. 1.

Referring more particularly to said drawings, in which like reference characters indicate like parts in the several views, the numeral 1 designates the stock of my instrument which is preferably of metal and in the form of an elongated casing having a 65 pocket 2 extending interiorly throughout its dimensions, the side-walls 3 and 4 of the casing being extended to provide the longitudinal oppositely disposed flanges 5 and 6. A plate 7 is fitted in the pocket 2 and fixedly 70 secured in place to the side-wall 4 by means of rivets or screws 8. This wall 4 and plate 7 are provided with corresponding and registering diagonal slots 9, and the curved elongated slots 10, while the plate 7 also 75 has a curved hook-shaped guideway or slot 11 and a guideway or slot 12.

As clearly illustrated in Figs. 1 and 2, the straight-edges or angle-arms 9', 10', 11', and 12' are pivotally mounted at their inner 80 ends in their respective slots 9, 10, 11, and 12. Their opposite ends are pivotally mounted in close adjacent relation, to a bar 13.

For the purpose of locking the straight-edges in any desired adjusted position I provide the internally threaded pivotal member 9'' with a threaded and headed locking bolt or set screw 14, the inner end of the bolt extending through the side-wall 3 of the casing, as clearly shown in Fig. 4, while the arm 10' has a similar locking device indicated at 10''.

The illustration, Fig. 2, shows the instrument set where the pitch begins or at 95 an angle of 45 degrees for the arm 12', while the dotted lines indicate a different lesser angle of adjustment of the straight-edges, showing the true positions of the several arms for indicating the proper angles 100 upon the rafters for making cuts for the joints.

In ascertaining the true angles for the cuts of the several rafters subordinate to the angle or pitch of the common rafters, the two set screws are first loosened to allow the straight-edges to be pulled out of the casing. The plumb cut for the common rafters having been determined with a steel square, a line is drawn on the rafter to in- 110

dicate the same. Then the angle-arm which represents the angle of plumb cut for the common rafter is placed parallel with this line and the locking screws tightened. The 5 angles of the cuts for the several rafters will be accurately indicated by the arms, as follows: arm 11' for the plumb cut of hip or valley rafters; arm 9' for the plumb cut of the common and jack rafters; arm 10' for the side cut of the hip or valley rafters; and arm 12' for the side cut of the jack rafters.

In every instance, the angles indicated by the arms represent the same purpose for 15 any adjusted pitch. When once set there can be no mistakes as the cuts are ascertained mechanically with absolute accuracy, it being understood that the adjustment of the master arm 9' from its pivotal point 20 X governs the adjustments of the several angle members automatically, as their movements are controlled by the curves of the slots in which they are respectively pivoted.

The curves for the slots are plotted by 25 first establishing the correct or true angles which the legs will assume under given conditions. The plumb cut of the common rafter edge constitutes the base from which the other cuts are gaged, and hence the 30 other edges must be adjusted to conform or correspond with the correlated cuts for a given pitch or predetermined angle of the common rafter plumb cut.

To secure these curves the master arm 35 or edge 9' is first set at 90 degrees to the straight edge of the stock and the correlated angles of the arms 10', 11', and 12' having been determined for that particular angle the arms are set at such angles and 40 dots made on the pattern piece for the stock to indicate the initial connecting points of the stock ends of the arms as clearly shown in solid lines in Fig. 2 of the drawings. The master arm or edge 9' 45 is then set at an angle to give a slight degree of pitch, say 85 or 87 degrees to the stock. The angles of said correlated arms or edges which, as heretofore explained, are intended to designate for all established 50 pitches of the master arm, the side cuts of jack rafters, the side cuts of hip and valley rafters, and the plumb cuts of hip and valley rafters, are then computed, the positions of the arms set to the correct angles 55 and dots used to indicate on the stock pattern piece the guide or stock connecting points for the respective arms. The foregoing operation is repeated successively, the

master arm being shifted by degrees, the correlated angles determined, and the dots used as before. All the desired angles having been thus ascertained and plotted, lines are then drawn connecting the dots for the respective arms, the curve for each slot being indicated by the lines. In the foregoing 65 explanation it is to be understood that the references to the "master arm" and the correlated arms are used figuratively, the actual plotting being made upon the usual pattern sheet, the several arms being of a 70 desirable or convenient length and the dimensions of the stock being such as to accommodate the scope of the slots.

From the foregoing description taken in connection with the drawings, it is apparent that I have provided a meritorious instrument of novel and advantageous construction, well adapted to fulfil the purpose for which it was designed.

Having described my invention, I 80 claim:—

1. An instrument of the character described, consisting of a stock member provided with a plurality of curvilinear correlated slots or guideways, an angle-arm pivotally mounted in each of said slots or guideways, and a master angle-arm pivotally mounted in said stock member, the outer ends of said arms being pivotally retained in adjacent relation. 90

2. An instrument of the character described, consisting of a stock member provided with a plurality of curvilinear correlated slots or guideways, an angle-arm pivotally mounted in each of said slots or 95 guideways, a master angle-arm pivotally mounted in said stock member, the free ends of said arms being adjustably retained in adjacent relation, and locking means for securing said arms in adjusted position relative to said stock member. 100

3. An instrument of the character described, consisting of a stock member having a straight edge and provided with a plurality of curvilinear correlated slots or 105 guideways, an adjustable angle arm slidably mounted in each of said slots or guideways, and an adjustable master angle arm pivotally connected to said stock member, the adjustment of the first mentioned 110 arms being mechanically and automatically controlled by adjustable movement of the master arm.

In testimony whereof I hereby affix my signature.

AXEL L. RUTQUIST.
